UNITED STATES PATENT OFFICE.

FERMAN M. DENNIS, OF LANSING, MICHIGAN.

DESIGN FOR A SHADE AND CURTAIN BRACKET.

45,903.

Specification for Design.

Patented June 9, 1914.

Application filed March 26, 1914. Serial No. 827,497. Term of patent 7 years.

To all whom it may concern:

Be it known that I, FERMAN M. DENNIS, a citizen of the United States, residing at Lansing, in the county of Ingham and State of Michigan, have invented a new, original, and ornamental Design for a Shade and Curtain Bracket, of which the following is a specification, reference being had to the accompanying drawing, forming part thereof.

Figure 1 is a perspective view of a shade

and curtain bracket, showing my new design; Fig. 2 is a side view; Fig. 3 is a front view; and Fig. 4 is a top plan view.

I claim:

The ornamental design for a shade and curtain bracket, as shown.

FERMAN M. DENNIS.
